UNITED STATES PATENT OFFICE

BORIS BLECHER, OF PHILADELPHIA, PENNSYLVANIA

DESIGN FOR A COLLAR HOLDER

Application filed October 3, 1930. Serial No. 37,116. Term of patent 14 years.

To all whom it may concern:

Be it known that I, BORIS BLECHER, a citizen of Latvia, residing at Philadelphia, in the county of Philadelphia and State of Pennsylvania, have invented a new, original, and ornamental Design for Collar Holders, of which the following is a specification, reference being had to the accompanying drawings, forming part thereof.

Fig. 1 is a front elevation of a collar holder showing my new design.

Fig. 2 is a top plan view of the same, and Fig. 3 is an elevational view of one end thereof.

I claim:

The ornamental design for a collar holder, substantially as shown.

In testimony whereof I have affixed my signature.

BORIS BLECHER.
